UNITED STATES PATENT OFFICE.

THOMAS L. BACON, OF DENVER, COLORADO.

ADJUSTABLE STAND.

935,730.

Specification of Letters Patent.

Patented Oct. 5, 1909.

Application filed September 28, 1908. Serial No. 455,140.

To all whom it may concern:

Be it known that I, THOMAS L. BACON, a citizen of the United States, residing at Denver, in the county of Denver and State of Colorado, have invented a new and useful Improvement in Adjustable Stands, of which the following is a specification.

This invention relates to an adjustable stand for supporting lamps, glasses and other small articles, and adapted to be clamped to the head post of a bed-stead, or the arm of a chair.

The invention consists in the novel features of construction, hereinafter described, pointed out in the claims and shown in the accompanying drawings, in which:

Figure 1 is a side elevation of my invention applied to a bed post. Fig. 2 is a plan view of the device, the post being in section. Fig. 3 is a detail perspective view showing the clamping sections detached from each other. Fig. 4 is a detail perspective view of the stand supporting bracket, the stand being removed.

In these drawings 1 represents the bed post to which is secured a clamp formed in two sections 2 and 3. Section 2 comprises a sleeve 4 from one side of which extends a flange 5 provided with a boss through which works a thumb screw 6, which screw carries a concaved plate 6^a, and the face of this plate may be padded or covered with cloth if desired in order to prevent injury to the polish of the post or chair arm. From the sleeve 4 also extends a flange 7 at right angles to the flange 5 and this flange has its inner face serrated by forming transverse grooves across the said face. The flange 7 is longitudinally slotted at 8, hereafter to be referred to.

The clamp 3 is a right angled plate one member of which has its outer face serrated to engage the serrated face of the flange 7, and this portion of the clamp section 3 is provided also with a threaded perforation which receives a set screw 9 which works through the slot 8 of the flange 7. The other member of the clamp section 3 is provided upon its inner face with a recess 10 which recess is opposite the concaved plate 6^a and when the device is applied to a bed post the post will fit between the recess member of the clamp and the plate 6^a, and by turning the screw 6 the post will be firmly gripped between these two members of the device. The set screw 9 will lock the clamp

members 2 and 3 together, the serrated faces preventing any movement between the two sections of the clamp relative to each other. A bracket 11 substantially V-shaped is provided with an arm 12 which extends from its apex portion and is then bent at right angles to form a pivot pin 13 which pin fits within the sleeve 4 and rotates therein. The stand 14 preferably formed of a smooth square board 60 or a thin metal plate with slightly rounded corners is secured upon the bracket 11 by riveting or by means of screws, and completes the device. When used upon a chair arm the plate 6^a bears upon one side of the 65 arm and the recessed member 3 of the clamp upon the other side, the flange 7 resting across the outer end of the arm. I also provide the sleeve 4 with two transverse bores 70 15 and 16, placed ninety degrees apart, and 75 into which the pin 13 can be placed, so that the stand can be attached when the clamp is fastened in position other than that shown in the drawings, and which enables the clamp to be applied to tables, a side rail of 80 a bed, or to other articles of furniture.

What I claim is:—

1. A device of the kind described comprising a sectional clamp formed of two members, one of said members comprising a 85 sleeve, flanges extending from said sleeve and at right angles to each other, a thumb screw working through one of said flanges, a set screw working through the other flange, said last mentioned flange being slotted and the 90 other member of the clamp comprising an angled plate one member of which is provided with a threaded perforation to receive the set screw.

2. A device of the kind described comprising a clamp formed in two sections, one of said sections comprising a right angled plate, one member of which is recessed upon its inner face, and the other member of which is serrated upon its outer face, the other section 100 of the clamp comprising a sleeve, flanges carried by said sleeve and at right angles to each other, one of said flanges being slotted longitudinally and serrated to engage the serrated face of the first mentioned section, a set 105 screw working through the slot and threading into the serrated member of the first mentioned section, a thumb screw working through the other flange, a concaved plate carried by said thumb screw, said plate being 110 opposite the recess of the first section, a bracket stand, and an angled arm carried by

said stand for engaging with the sleeve, as and for the purpose set forth.

3. A device of the kind described comprising a sleeve having intersecting bores at right angles to each other, flanges extending from one side of said sleeve and at right angles to each other, one of said flanges being provided with a perforated threaded boss, and the other with a longitudinal slot, and a right angled plate adapted to grip a post and resting in the angle formed by said flanges, a thumb screw working through the

boss, a concaved plate carried by the inner end of said thumb screw and coöoperating with the opposing face of the right angled plate, a set screw working through the slot of one of the flanges and engaging the right angled plate, and suitable stand supporting means in rotatable engagement with said sleeve. 15
